COMBINED TROUSER HANGER AND TRAY

Clifford P. Sivertson, Wheaton, Md.

Application May 6, 1955, Serial No. 35,868

Term of patent 14 years

(Cl. D33—3)

FIG. 1.

FIG. 2.

FIG. 3.

Figure 1 is a perspective view of the combined trouser hanger and tray, showing my new design, looking to the front and one side thereof;

The back of the supporting plate member is substantially plain.

I claim:

The ornamental design for a combined trouser hanger and tray, as shown and described.
